CLAIM

An ornamental design for a needle protector, as shown and described.

DESCRIPTION

FIG. 1 is a first embodiment of a perspective view of a needle protector showing my new design;

FIG. 2 a front elevation view thereof;

FIG. 3 a rear elevation view thereof;

FIG. 4 a left side elevation view thereof;

FIG. 5 is a right elevation view thereof;

FIG. 6 is a top plan elevation view thereof;

FIG. 7 is a bottom plan view thereof;

FIG. 8 is a second embodiment of a perspective view of a needle protector showing my new design;

FIG. 9 is a front elevation view thereof;

FIG. 10 is a rear elevation view thereof;

FIG. 11 is a left side elevation view thereof;

FIG. 12 is a right elevation view thereof;

FIG. 13 is a top plan elevation view thereof;

FIG. 14 is a bottom plan view thereof; and,

FIG. 15 is an enlarged perspective view of a hole and button feature in FIG. 1 for a needle protector, according to embodiments of the disclosure.

The views described herein are used to denote front, top, bottom, rear, and side views of embodiments of the disclosure and are not to be interpreted as limiting the orientation of the Needle protector. It is to be understood that a disclaimed button as in FIG. 1 may also be contemplated within FIG. 8. It is to be further understood that FIGS. 1–7 are mirror images of FIGS. 8–14.

The broken lines show portions of the needle protector that form no part of the claimed design.
